TELEVISION SYSTEM

Irl R. Goshaw, Nutley, N. J., assignor to Wired Radio, Inc., New York, N. Y., a corporation of Delaware

Application May 11, 1932, Serial No. 610,546

7 Claims. (Cl. 178—6)

This invention relates to television systems and particularly to such systems of the non-mechanical type wherein no mechanical movements are employed although such movements may be substituted for non-mechanical elements if desired.

5 An object of the invention is to transmit images of objects with electrical currents.

Another object of the invention is to generate and transmit currents corresponding to the light 10 and shade densities of an object and to translate such currents into light images of said objects at a distant point.

A further object of the invention is to transmit light images of objects with a system employing 15 non-mechanical movements.

A still further object of the invention is to provide a television system for transmitting images by transmitting only certain portions of an image characterized by a certain light density.

20 In the usual type of television transmission system, an object or image thereof is scanned by a flying light spot or electron stream to analyze the object or image into unit areas for serial transmission to similar apparatus for building 25 up the image in the same or an equivalent manner. These systems have many disadvantages such as the frequency limitation of the apparatus, the difficulty of synchronizing moving elements at the transmitter and receiver, the difficulty in 30 obtaining sufficient detail and good definition because of the rapid movement and short duration of a unit light area, and, where mechanical moving elements are employed, the limitation by speed and size to a small picture area.

35 The television system disclosed hereinafter requires a less efficient line than the present type since the line carries less load for the same detail as now obtained while the size of the picture is not limited because no mechanical movements are 40 employed for analyzing or building up the images. Synchronization is natural in that the house supply current may supply the transmitter and receiver directly, or synchronization may be obtained by simple tuning as in a radio receiver.

45 It is to be understood that mechanical elements may be substituted for certain electrical elements, these mechanical elements being of so simple a nature that they may be taken bodily from present picture projection systems now in general use.

50 The chief principle of the invention is the electrical delay of currents so that a serial relationship is produced from a plurality of generators operating simultaneously. For instance, a composite cathode of a photoelectric cell is employed, the cathode being formed of many in-

dividual cells having a common anode, each cell corresponding to a unit area of the image of an object to be transmitted. At the receiver a similar but reversed graduated delay system is employed in which a picture is obtained by voltage flashes at the proper rate of speed modified by the incoming picture currents.

55 The invention will be more fully understood from the following description read in conjunction with the accompanying drawing in which:

Fig. 1 is a diagrammatic view of the transmission system;

Fig. 2 is a detailed plan view of a cathode of the photoelectric cell;

Fig. 3 is a diagrammatic view of the receiving 70 apparatus;

Fig. 4 is a graph of the television currents in the output of the transmitter; and,

Fig. 5 is a circuit element which may be substituted for a portion of Fig. 3.

75 Referring specifically to Fig. 1, an object O is illuminated with intermittent light from a lamp 5 supplied by an alternator 6 or from the house supply source. The image of the object so produced is focussed by a lens 8 upon a composite cathode 9 of a photoelectric cell having an anode 10. The projecting lamp produces on the cathode 9 intermittent light images which occur at double the frequency of the source 6. Intermittent images may also be produced on the cathode with 85 a constant illumination of the object O but which is broken up by a shutter 12 operated by any means well known in the art.

90 In Fig. 2 a plan view of the cathode 9 of the photoelectric cell shows a cathode divided up into a plurality of sections which are insulated from one another by thin insulating partitions such as layite or mica. The back of the cell is formed of sections of conducting material insulated from one another but which have deposited thereon the photosensitive material. This construction forms many individual photoelectric cells independent of one another electrically but which have a common anode 10. To each cell unit is connected a conductor and as shown in Fig. 1 they are brought 95 out to a common lead or busbar 14. In all conductors but one there are inserted delay elements 16, such as inductances of graduated values which have the proper amount of distributed capacity to produce a small difference in delay in each circuit. To maintain the direct current impedances in each circuit constant there is also inserted in the conductors a graduated series of pure resistances the direction of graduation being the reverse of the delay element 16. As stated above, 100 105 110

the conductors terminate in a busbar 14 connected to the input of an amplifier 20, the other input lead being connected to the anode 9 of the photo-cell by conductor 21. The output of the amplifier 20 is fed into a transmitter 22, from which it may be broadcast over an antenna 23, or wire conductors 24.

The operation of the transmitter is as follows: Intermittent images at any desired rate such as 10 twenty per second, which is the present transmission rate, or higher are impressed upon the cathode 9. At each image impression the unit areas receiving light above a certain density will simultaneously generate currents proportional to 15 the light falling thereon. The generated impulses will not arrive at the amplifier 20 simultaneously, however, but in a serial order, the time unit between the first and last impulse depending upon the delay inserted in each particular circuit. The 20 amount of delay is determined by the period of illumination of the cathode and the number of unit cells or areas employed. With present standard television practice, the number of individual cells would be in the neighborhood of 3600 and 25 the intermittent illumination at the rate of twenty per second, making the delay in each circuit on the order of 1/72000 of a second. The amount of damping of the light impulses is immaterial as 30 will be seen later but a sharp impression of the impulses upon the cathode is required.

In Fig. 4 a time interval between the impression of light impulses is shown which may be an interval of 1/20 of a second between "a" and "b", the first and last impulse, respectively. The 35 variation in the current arriving at the amplifier 20 is shown by this curve. The portion of no current near the middle of the interval is indicative of a dark area running across the middle of the cathode such as would be formed by the object O with the delay graduated in a vertical direction.

Referring now to the receiving apparatus in Fig. 3, an antenna 30 or wire conductors 31 impress incoming energy upon a receiver 32. After 40 reduction to the original impulses in the receiver they are amplified in an amplifier 34 which is connected to a busbar 35 and conductor 36. The receiving screen is in appearance similar to the cathode of Fig. 2 but the elementary 45 areas are formed of either individual neon lamps or incandescent lamps which have common electrodes 37 and 40. The other electrodes or grids of the lamps are connected to the busbar 35 through delay circuits 38 having varying amounts 50 of delay and pure resistances 39 identical to the arrangement in Fig. 1.

Between the common electrode lead 36 and electrode 37 there is connected a source of direct potential 41 shunted by a variable condenser 42, a 55 variable inductive element 43 and a variable resistance 44. These three elements shown within the dotted lines serve as the trigger for the receiving screen and provide, in connection with the neon lamps, a relaxation oscillator system. That 60 is, a voltage from a source 41 will build up to the point of flashover and the discharge of the condenser 42 will light the lamps for an instant. This interval of operation depends upon the tuning of the elements 42, 43 and 44, and may be 65 varied within wide limits, this relaxation action being well known in the art.

Fig. 5 shows a detailed circuit which may be substituted for the portion of Fig. 3 shown within the dotted lines or in other words the relaxation oscillator circuit. A source of direct current po-

tential 50 is connected between the screen and amplifier through a contact 51 shunted for condenser 52 by protecting the contacts 51. The contacts 51 are operated by a relay 54 which may be connected to the ordinary 60 cycle alternating current house supply. The relay may be made to operate the contacts 51, 60 times per second or 120 times per second by a direct connection to the house tap. The receiving screen when used with the circuit of Fig. 5 may be either individual neon lamps, incandescent lamps, or in fact, merely arc gaps across which a current will flow at the proper voltage.

The operation of the receiver is as follows: The train of impulses shown in Fig. 4 arrive at the busbar 35 and conductor 36 after detection and amplification. As the impulses arrive they are delayed in proportion to the amount of delay in each individual circuit which is the same as the delay in the circuits at the transmitter. If we assume an impulse "a" as the first impulse, that particular impulse will arrive at the receiving position "a" on the screen at a certain instant of time. That same impulse of course, will arrive at the other light producing positions previous to its arrival at the position "a" but will be dissipated until the desired impulse wanted at the other positions arrive thereat. Taking the receiving cell conductor that has no delay whatever, which in this case is impulse "b" or the last impulse, all of the preceding impulses will arrive at the light element "b" before the last impulse and will be dissipated. However, at a certain instant of time every impulse will be at its proper element, which, with the assumed figures above, will be 1/20 of a second after the first impulse arrives at the busbar 35. At this instant a voltage will be built up from the source 41 sufficient to flash the neon lamps between the electrodes 37 and 40, the voltages on grids 33 determining the light intensities of the unit areas, or the contact 51 will be closed to connect the source 50 to the screen. Other sources of light such as incandescent lamps and the coordinate system of arc gaps are preferable with the circuit of Fig. 5.

The common voltage impressed is sufficient to light all lamps with the same intensity but because of the supplementing of the common voltage with the incoming impulse voltages at the various lamps each light will produce varying intensities corresponding to the light and shade densities of the object. When the lights are flashed by the common voltage an image will be observed on the screen corresponding to that projected on the cathode 9 at the transmitter. It is not necessary that the lamps be extinguished for the dark portions of the object, as long as there is a variation between the elements so that the brighter ones cause the lighter ones to appear as darker portions.

In the system above described, it is to be observed that by using the lamp source 5 connected to the alternating house supply, the object O may be illuminated 60 times a second by using a rectifier, or 120 times per second without the rectifier. Thus illuminated there will be sent to the receiver a train of impulses 60 and 120 times per second, respectively, each train comprising an image. The circuit of Fig. 5 is especially desirable at the receiver in this case, the relay 54 being similarly controlled to make contact 60 or 120 times per second by the ordinary house current supply solving the synchronizing problem in areas supplied from a common power system. At this rate, flicker is absolutely eliminated. In using 150

the relaxation oscillator it is only necessary to vary the tuning of the elements making up the oscillators in a manner similar to the tuning of any radio receiver. The transmitting apparatus 5 using the shutter type of light interrupter may be simply that of a moving picture camera or projector which can be operated manually or by a spring motor well known in the motion picture art. With the convenient tuning operation at 10 the receiver, the manual or motor drive is easily synchronized. It is to be understood that the receiver may operate without a trigger system. That is, a constant voltage sufficient to energize 15 the lamps to a certain brightness is applied to the screen and a shutter similar to the one at the transmitter or of the multiple opening type exposes the lamps to view at the instant the proper illuminating voltages are present at the lamps.

The invention has been described to emphasize 20 such advantages as non-mechanical apparatus, simplicity of operation, the method of operation which provides positive detail for each individual element, and the efficient use of transmission lines since only the light portions of the object 25 are transmitted. The scope of the invention is defined by the appended claims.

What is claimed is:

1. In an electrical transmission system for transmitting currents characterized by the light 30 and shade intensities of an object, the combination of means for simultaneously obtaining a plurality of currents proportional to the light intensities of unit areas of an image, electrical delay networks for distributing said currents in a 35 transmission line in a serial order, and electrical delay networks for impressing said currents upon a plurality of light producing devices simultaneously.

2. An electrical transmission system for the 40 transmission of currents corresponding to the light and shade intensities of an object, means for simultaneously producing currents corresponding to the light intensities of a plurality of unit areas of an object, electrical delay networks 45 for delaying the transmission of said currents in a graduated order, means for transmitting said currents to a receiving point, a plurality of light producing elements at said receiving point, and electrical delay networks for delaying said currents in the reverse graduated order for simultaneously 50 impressing on said light producing elements energy corresponding to the light intensities of the unit areas at said transmitter.

3. In a television system, a composite cathode 55 comprising a plurality of individual unit sections, means for intermittently impressing an image thereon, an electrical delay network for impressing the currents generated from said unit section in serial order on a transmission line, a plurality of light producing elements at a receiving 60 point at the terminal of said transmission line, and a plurality of individual circuits including electrical delay elements connected to said light producing elements for simultaneously impressing upon said elements the currents generated by the light affected sections of said composite cathode.

4. In a television system, the combination of

a composite cathode having a plurality of individual light sensitive areas, an anode for all of said areas, means for impressing an image on said cathode intermittently for producing electrical impulses, a transmission line, an electrical delay network connected to said line for impressing the impulses from said cathode upon said transmission line at definite mutually exclusive instants of time, a receiver at the terminal of said transmission line, and a similar network at 80 said receiver for re-arranging said impulses so that they appear simultaneously.

5. In a television system, means for simultaneously obtaining electrical impulses corresponding to the light intensities of a plurality of unit areas of an object, a single channel transmission line, an electrical delay network connected to said line for transmitting said impulses over said single channel transmission line while maintaining a separation between impulses, a plurality of light producing elements corresponding to unit areas at said first means, and a similar network connected to said transmission line for simultaneously impressing said impulses on said light producing elements in accordance with their generation at said first means.

6. In a system for transmitting currents characterized by the light and shade intensities of an object, the combination of a plurality of photo sensitive means for producing electrical currents, means for illuminating said object from an alternating current source, a transmission line, an electrical delay network connected to said line for distributing the currents from said plurality of photo sensitive means in said transmission line in a serial order, a plurality of sources of light for reproducing an image of said object, an electrical delay network connected to said line and to said light sources for distributing said currents to said light sources simultaneously, and means connected to said plurality of light sources for actuating said light sources from an alternating current source.

7. An electrical transmission system for the transmission of currents corresponding to the light and shade intensities of an object, means for simultaneously producing current impulses corresponding to the light intensities of unit areas of an object, means for illuminating said object with light from a source energized from an alternating current source, an electrical delay network for distributing said impulses from said first mentioned means in a serial order between the nodes of the currents in said alternating current source, means for transmitting said currents to a receiving point, a plurality of light producing elements at said receiving point, an electrical delay network for distributing said impulses in reversed order on said light producing elements, and means connected to an alternating current source for controlling the actuation of said light producing elements, the production of said currents and the reproduction of the received image of the object being in synchronism, when said alternating current sources have the same frequency.
